Henry H. Barreda. Inventor.

By *James Sangster*, Attorney.

UNITED STATES PATENT OFFICE.

HENRY H. BARREDA, OF BUFFALO, NEW YORK, ASSIGNOR TO HIMSELF
AND HARRY M. ROSE, OF SAME PLACE.

CAPE-SUPPORT FOR BICYCLES.

SPECIFICATION forming part of Letters Patent No. 594,513, dated November 30, 1897.

Application filed December 24, 1896. Serial No. 616,890. (No model.)

To all whom it may concern:

Be it known that I, HENRY H. BARREDA, a citizen of the United States, residing at Buffalo, in the county of Erie and State of New York, have invented certain new and useful Improvements in Cape-Supports for Bicycles, of which the following is a specification.

My invention relates to an improved cape-support for bicycles, adapted to be attached thereto to hold the front portion of a waterproof cape or covering from contact with a rider's limbs.

It also relates to certain details of construction and will be fully and clearly hereinafter described and claimed, reference being had to the accompanying drawings, in which—

Figure 1 represents a perspective view of a bicycle, its rider, and the waterproof cape or covering, showing the waterproof cape in position on the rider. Fig. 2 represents a face view of the waterproof cape. Fig. 3 is a top view of the cape-support. Fig. 4 represents a rear side view of the said supporting device, illustrating also a detached portion of the head-tube of a bicycle-frame to which it is attached. Fig. 5 represents a side elevation of a portion of the head-tube and upper frame-bar of a bicycle-frame, also showing the waterproof cape rolled in a small package and secured to the said upper frame-bar.

Referring to the drawings in detail, I designate the waterproof cape or covering by the numeral 1. It is constructed of any well-known waterproof material and preferably in the rectangular form shown in Fig. 2. It is provided with an opening 2, through which the head of the wearer is introduced, straps 3 and buckles 4 for securing it to a bicycle-frame, and a pocket 5, the object of which will be explained farther on.

The cape-support consists of a clamp composed of two semicircular portions 5^a 5^b, pivotally secured to each other at one end by the hinge 6 and detachably at the opposite end by a thumb-screw 7. A tubular screw-threaded ear 7^a projects outwardly from each of said semicircular clamping portions 5^a, and the outward-extending supporting-arms 8 are provided with screw-ends 7^b, adapted to screw into said ears.

When the rider desires to protect himself from rain or other unpleasant weather, he passes his head through the opening 2 and

arranges the waterproof cape around him substantially as shown in Fig. 1.

The support is clamped to the head-bar of the bicycle-frame about midway between the handle-bar and the fork-crown, and the supporting-arms 8 extend outward from each side of said head-bar and thus support the lower front portion of the waterproof cape against the wind occasioned by the passing of the bicycle through the air and prevent the same from coming in contact with the rider's limbs and thereby interfering with or retarding the free action of said limbs in operating the bicycle.

When the cape and the support are not required for use, the supporting device can be unclamped from the bicycle-head and the two arms 8 folded together and placed in the pocket 2. The waterproof covering can then be rolled up and secured to the bicycle-frame substantially as shown in Fig. 5.

It may be advisable if the rider desires to carry the waterproof covering and the supporting device on the wheel at all times to place a second pocket 2^a in the said covering to receive the various repair implements, wrench, pump, &c.

I claim as my invention—

1. A supporting device, consisting of two semicircular clamping portions secured to each other at one end by a hinge and at the other by a thumb-screw, a tubular screw-threaded ear projecting outwardly from each of said clamping portions and supporting-arms provided with screw-threaded ends engaging in said ears, as set forth.

2. A device adapted to be attached to a bicycle for supporting the front of a waterproof covering from contact with the rider's limbs, comprising two semicircular clamping portions pivotally hinged to each other at one end, and having extensions provided with circular screw-threaded openings at their opposite ends, a thumb-screw fitting said openings, a tubular screw-threaded ear projecting outwardly from substantially the middle of each of said clamping portions, and straight portions having one end screw-threaded to fit and engage in the ears, as set forth.

HENRY H. BARREDA.
